Melton Mowbray, Leicestershire, England

Filed June 29, 1967, Ser. No. 7,634

Claims priority, application Great Britain Jan. 3, 1967

Term of patent 14 years

(Cl. D96—12)

FIG. 1.

FIG. 2.

FIG. 3.

FIG. 4.

FIGURE 1 is a perspective view taken from the front, top and one side of a sign panel for a door or the like showing my new design;

I claim.

The ornamental design for a sign panel for a door or the like, substantially as shown.
